UNITED STATES PATENT OFFICE.

IRA H. RHINDRESS, OF OXFORD, NOVA SCOTIA, CANADA.

MILK-BOTTLE SAFE.

Application filed March 21, 1928. Serial No. 263,558.

This invention relates to new and useful improvements in containers, and more particularly to a container for milk bottles.

An object of this invention is to provide 5 an article of the character described, having a door that will lock only at such times when a milk-bottle or other object is deposited therein.

Other objects and many of the attendant 10 advantages will be readily appreciated as the invention becomes better understood from a consideration of the illustrative embodiments of the same and for which purpose such descriptive drawings have been 15 hereto appended wherein:

Fig. 1 is a perspective view of the invention.

Fig. 2 is a broken, perspective view of the container, showing the latching mechanism.

Fig. 3 is a section on the plane of line 3—3, Fig. 1 looking in the direction indicated by the arrows.

Referring more in detail to the drawings 25 in which similar reference numerals designate the corresponding parts throughout the several views, it will be seen that the container 6 is provided with a suitable door 7 mounted upon hinges 8 in a manner to swing into the 30 container and is prevented from swinging outwardly by lugs 5 which outstand from the margin thereof. A lock 9 is attached to the margin so that its latch-bolt 10 will normally project. This latch-bolt 10 has its forward edge beveled as at 11 and is normally disposed in "thrust" position by the tension of a spring within the lock, and may only be withdrawn by a key, for which is provided a key-hole 12.

40 The latch-keeper comprises a plate 14 hinged by its upper margin as at 15 to the container, and prevents retention of the latch-bolt 10. This plate 14 is effected to normally remain in depending position by 45 the tension of spring 13.

A base-plate 16 is disposed within the container. This base-plate is rockably mounted upon a spindle 17, intermediate its ends, and has an arcuate portion punched 50 from one of its forward corners as at 18 to allow free swinging movement of the door 7. The other forward corner of the plate 16 serves as an arm and has a bolt 19 connected thereto. This bolt is supported in 55 vertical position by slidably passing through orifices 20 produced in ears 21 of bracket 22

which is attached to the container 6 and disposed just below the latch-keeper. An expansion coil spring 23 is disposed around the bolt 19, between the plate 16 and lower 60 ear 21 in a manner to effect and keep the forward portion of the base-plate 16 in normal, depressed position together with the connected bolt 19 which will be withdrawn from engagement with the latch-keeper. 65

In operation, it will be seen that when the container 6 is empty the operating parts will be in normal position, that is the base plate 16 will be depressed at the front by the tension of spring 23 which will also 70 cause the connected bolt 19 to be withdrawn from engagement with the latch-keeper, thus the hinged plate 14 will be free to move, thereby preventing retention of the latch-bolt 10 and consequent locking of the door 75. When a bottle of milk or similar article is deposited in the container 6 and upon the base-plate 16, the weight will cause the plate to rock so that the forward portion will be raised together with bolt 19 which 80 will then extend to adjacent relation with the hinged-plate 14 of the latch-keeper locking it against movement, thus when the door 7 is closed, the latch-bolt 10 will engage the keeper, locking the door until the bolt 10 85 is withdrawn by a key inserted in the key-hole 12. When the bottle or article is removed from the base-plate 16, the elements return to normal position and the hinged plate 14 of the latch-keeper is released, thereby preventing retention of the latch-bolt 90 until a further article is deposited within the container.

It will be obvious from the foregoing description that this invention is a great and 95 novel improvement in containers and whilst the preferred embodiments have been disclosed yet it is to be understood that minor changes in the details of construction and arrangement of the co-operating elements 100 may be resorted to within the scope of what is claimed without departing from the spirit of the invention.

What I claim is:

1. In a container; a door, said door being hinged; a lock attached to said door; a keeper to co-act with said lock, said keeper comprising a plate, hingedly connected at its upper edge so as to be free to move; a base-plate disposed in the bottom of the 110 container, said base-plate being rockably pivoted intermediate its ends; a bracket hav-

ing an orifice therein; a bolt connected to said base-plate at the forward edge thereof, said bolt extending upward through said orifice within said bracket and terminating adjacent said hinged plate of said keeper; and an expansion coil-spring disposed around said bolt intermediate said base-plate and said bracket as and for the purpose specified.

2. In a container; a door, said door being hinged; a lock attached to said door, said lock having a spring-tensioned latch-bolt which is normally in thrust position, said latch-bolt having its forward edge beveled; a keeper to co-act with said lock, said keeper comprising a plate, hingedly connected at its

upper edge, so as to be free to move; a base plate disposed in the bottom of the container, said base-plate being rockably pivoted intermediate its ends; a bracket having ears; an orifice in each of said ears; a bolt connected to said base plate at the forward margin thereof, said bolt extending upwardly through each of said orifices in said ears of said bracket and terminating adjacent said hinged plate of said keeper; and an expansion coil spring disposed around said bolt intermediate said base-plate and said bracket as and for the purpose specified.

In testimony whereof I affix my signature.

IRA H. RHINDRESS.
